UNITED STATES PATENT OFFICE.

ALVA ARTHUR LINDLEY, OF SPOKANE, WASHINGTON.

BOILER FITTING OR CONNECTION.

Application filed October 20, 1921. Serial No. 509,074.

To all whom it may concern:

Be it known that I, ALVA ARTHUR LINDLEY, a citizen of the United States, and a resident of Spokane, in the county of Spokane and State of Washington, have invented certain new and useful Improvements in Boiler Fittings or Connections, of which the following is a specification.

10 My invention relates to an improvement in boiler fittings or connections especially adapted for use in conjunction with a boiler of the character shown in my copending application for water tube boiler, filed April 14, 1921, Serial No. 461,296.

15 The object of the invention is to provide a boiler connection or fitting of this character which eliminates the necessity of utilizing packing, which is endowed with great 20 strength and rigidity so as to afford a mechanical connection as well as a fluid connection and yet at the same time have ample capacity for adjustment; and which is in general of simple and durable construction, reliable and safe in operation and easy 25 and inexpensive to manufacture.

Other objects and advantages of the invention reside in certain novel features of construction, combination and arrangement 30 of parts which will be hereinafter more fully described and particularly pointed out in the appended claims, reference being had to the accompanying drawings forming part of this specification, and in which:

35 Figure 1 is a view in side elevation, illustrating the preferred embodiment of the invention, the adjacent structure of the boiler being broken away;

Figure 2 is a view in longitudinal vertical section;

Figure 3 is a view in transverse vertical section on line 2—2 of Figure 1;

Figure 4 is a detached view of the connection or coupling, showing the same arranged in one of its angular positions; and

Figure 5 is a detail view, illustrating the connection of the bolt head to the coupling flanges.

Referring to the drawings wherein for 50 the sake of illustration is shown the preferred embodiment of the invention, the numerals H and H' designate boilers which are connected or coupled by means of a fitting, designated at K and constituting the present invention.

This fitting includes connections or coupling members, designated at 10 and 11. The coupling members are welded or otherwise secured to the boilers and are provided with axial openings or bores 12 and 13, respectively which extend through the coupling members and open into the interior of the boilers. The coupling members are provided with sockets or seats, designated at 14 and 15, respectively and extending laterally from the coupling members adjacent said seats are coupling flanges 16 and 17 which are arranged in opposed or confronting relation in the assembly. A ball, designated generally at 20 is preferably constructed of brass and is arranged between the coupling members 10 and 11. The ball 20 comprises two semi-spherical sections 21 and 22 having their abutting faces 21^a and 22^a machined or otherwise formed to provide a ground joint therebetween. The periphery of the ball and the surface of the seats 14 and 15 are also machined or otherwise formed to provide a ground joint between the ball and these seats. The sections 21 and 22 are each provided with a frusto-conical opening, designated at 21^b and 22^b, respectively, the frusto-conical openings having their smaller ends arranged at the center and their larger ends at the periphery of the ball whereby the walls of the opening contract or converge toward the center and diverge or flare outwardly toward the periphery of the ball. Bolts and nuts, designated at 25 coact with the coupling flanges 16 and 17 and secure the coupling members to sections of the ball in assembly. Bolt heads 25^a of the bolts 25 operate on curved bosses 26 provided on the coupling flanges and the shanks of the bolts 25 adjacent the bolt heads 25^a operate in double frusto-conical openings 27 provided therefor in the coupling flanges and presenting a fulcrum or ridge 28 on which the shank of the bolt operates. By associating the bolts and the coupling flanges in this manner the angular disposition of the coupling flanges which occurs when the coupling members are disposed in angular relation with respect to each other is compensated for.

In use when the fitting is in assembly and the bolts and nuts 25 are tightened they operate by means of the coupling flanges 16 and 17 to draw the coupling members 10 110

and 11 toward each other and cause the coupling members to powerfully engage the sections of the ball and the sections of the bolt to powerfully engage each other with the ground joint between the sections of the ball and the seats of the coupling members and the ground joint between the contacting faces between the sections of the ball operate to make the connections steam-tight. By constructing the sections of the ball with frusto-conical openings and relating these frusto-conical openings in the manner described the ball presents a cross section which is well adapted to stand up under the compression strains to which it is subjected and at the same time afford a passage for the steam or other fluid through the connection. Moreover the pressure is effective to supplement the action of the bolts 25 in forcing the sections of the ball into engagement with each other. The sectional ball facilitates the assembly and disassembly as well as the adjustment of the fitting and especially so in the crowded spaces in which the invention is usually utilized. In this manner the invention provides a boiler fitting or connection which eliminates packing and provides the necessary strength and rigidity to afford a mechanical as well as a fluid connection.

I claim:

1. In a device of the character described, a pair of coupling members having axial openings and seats, a ball consisting of semi-spherical sections having a ground joint between their contacting faces, the sections of

the ball being received on the seats of the coupling members and ground joint being provided between the sections of the ball and the seats of the couplings, the sections of the ball having communicating openings therein, coupling flanges carried by the coupling members and bolts coacting with said coupling members and bolts coacting with said coupling flanges for securing the coupling members and ball in assembly. 40 45

2. In a device of the character described, a pair of coupling members having seats, a ball consisting of semi-spherical sections coacting with said seats, said sections and said seats having a ground joint between them, and means for maintaining said coupling members and said ball in engagement with each other. 50

3. In a device of the character described, a pair of coupling members having seats, a ball received on said seats, said seats and said ball having a ground joint between them and means for clamping said coupling members in engagement with said ball in any of a plurality of angular positions with respect to each other comprising coupling flanges carried by the coupling members and bolts and nuts coacting with the coupling flanges, said bolts including a head and a shank and said coupling flanges having a curved boss provided with an elongated opening, the flange having a double frusto-conical opening presenting a fulcrum upon which the shank of the bolt operates. 55 60 65
